UNITED STATES PATENT OFFICE.

HARRY RANDOLPH VAN DEVENTER, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

INTERRUPTER FOR IGNITION-DYNAMOS.

1,191,856.

Specification of Letters Patent.

Patented July 18, 1916.

Application filed October 20, 1914. Serial No. 867,563.

To all whom it may concern:

Be it known that I, HARRY RANDOLPH VAN DEVENTER, a citizen of the United States, residing at Sumter, in the county of Sumter and State of South Carolina, have invented certain new and useful Improvements in Interrupters for Ignition-DYNAMOS, of which the following is a specification, reference being had to the accompanying drawing.

My invention relates to interrupters for magnetos and has for its object the production of an interrupter that will be simple and cheap to manufacture and in which no platinum contacts are necessary.

Another object is to provide an interrupter in which the contact surfaces are kept clean and bright by frictional rubbing.

A further object is to provide an interrupter that is quick acting.

Interrupters as employed on ignition generators, or as they are commonly termed "magnetos," usually consist of a fixed contact member having a platinum tip, and a movable member carrying a second contact point, the movable member by suitable means being caused to make and break contact with the fixed member at a certain place or places in each revolution of the magneto shaft by which the movable element is operated. Such devices are open to several objections, the principal one being that owing to the cost of platinum, the contact points are made relatively small, and a slight amount of oil or dirt prevents them from making a good contact, thereby affecting the operation of the magneto.

Another objection is the sparking which takes place owing to the small area of the contacts, and a further objection is the difficulty in maintaining even contact surfaces on the points and the fact that careful and often difficult adjustment is necessary if the points are removed for cleaning, etc.

In the accompanying drawing, Figure 1 is a front view of an interrupter embodying my invention. Fig. 2, a side view partly in section of same showing the circuit connections thereto, the interrupter contacts being closed, and Fig. 3, a view partly in section showing the interrupter contacts open.

Like figures of reference denote the same parts wherever they are shown.

1 denotes the end plate of the interrupter

which is usually mounted on the end of the magneto. This plate carries a collector ring 2, which is insulated from the plate by suitable insulation 3. The shaft of the magneto is shown at 4 and upon this shaft is suitably mounted an arm 5 carrying a spring 60 arm 5^a to which is attached at its outer end, a brush 6. The arm 5 may be readily removed, or adjusted in any radial position in relation to the shaft by any suitable means, such as screw 7. A cam 8 is mounted on the 65 end plate arranged to engage a projection 9 carried by the arm 5^a so that when 5 rotates over the cam the brush 6 which is normally in contact with the ring 2, will be suddenly lifted therefrom. This sudden 70 lifting of the brush is necessary, and I consider same to be one of the important features of my invention. Of course more than one cam 8 may be employed, so as to cause more than one interruption per revolution. 75 It is essential in a magneto that the interrupter contact be suddenly broken. It will not suffice to have a cut-away portion or insert of insulation somewhere in the ring as I have indicated at 10, for at slow speeds 80 the breaking of the circuit would not be abrupt, but would be gradual as the end of the brush would gradually slide from ring 2 on to the open space or insulation 10. This would mean a gradual break instead 85 of the abrupt break which is essential and which I obtain by my cam arrangement.

It will be observed that the brush 6 is at all times in rubbing contact with the ring 2 except when lifted away by 9 passing over 90 the cam 8. This keeps the contacts bright. It will also be observed that the ring 2 may be made of any suitable inexpensive metal such as brass, and the brush 6 may be of the ordinary woven wire-type impregnated with 95 graphite so as to be self-lubricating, and that the brush can be given a large area so that the resistance of the interrupter will be reduced to a minimum.

In Fig. 2 the circuits of a magneto are 100 shown, the primary 11 and condenser 12 being in multiple with the interrupter contacts. One end of the secondary 13 is connected to the ground or frame of the magneto, while the other end is connected to the 105 usual spark plug indicated at 14. It will be understood that the windings 11 and 13 are the generating windings of the magneto.

I have not shown any of the structural details of a magneto as it is obvious that my improved form of breaker mechanism may be readily adapted for use in connection with any type of magneto in which interrupter mechanism is used.

I claim:

1. In an ignition dynamo, interrupter mechanism comprising fixed and movable members in slideable contact, and means operated by said dynamo for separating said members whereby the entire surface of said movable member is raised from said fixed member.
2. In an ignition dynamo, interrupter mechanism comprising fixed and movable members in slideable contact, and means operated by said dynamo for causing a break between said members whereby said movable member is lifted from sliding contact with said fixed member.
3. In an ignition dynamo, interrupter mechanism comprising fixed and movable members in slideable contact, and means operated by said dynamo for causing a break between said members, said means comprising cam operated mechanism whereby the movable member is lifted from sliding contact with the fixed member.
4. In an ignition dynamo, interrupter mechanism comprising members in sliding contact, and rotary means operated by said dynamo for suddenly breaking said contact by lifting one of said members from the other.
5. In an ignition dynamo, interrupter mechanism comprising a relatively fixed member, a second member rotating in sliding contact with said fixed member, and means operated by said dynamo for separating said members without stopping the rotation of

said second member, substantially as described.

6. In an ignition dynamo, interrupter mechanism comprising a contact ring, a shaft, an arm on said shaft, a brush on said arm in sliding contact with said ring, and rotary means operated by said dynamo for suddenly raising said brush from said ring. 45

7. Interrupter mechanism comprising a contact ring, a revoluble shaft, a brush carried by said shaft in sliding contact with said ring, means whereby said brush is raised from said ring for a portion of each revolution of said shaft, and means for radially 50 adjusting said brush in relation to said shaft.

8. In an interrupter for ignition dynamos, the combination of a movable member having a radial path of travel, a fixed contact, a contact carried by said movable member and 55 in contact with said fixed member for completing a circuit, and means for suddenly moving said contact at right angles to its radial path of travel, and out of contact with said fixed member, substantially as described. 60

9. In an interrupter for ignition dynamos, the combination of a supporting plate, a collector ring carried thereby but insulated therefrom, a rotating contact member in contact with said ring, and means for suddenly separating said rotating contact from said ring whereby the entire surface of said rotating contact leaves said ring at the same time, during a portion of each revolution of 70 the dynamo, substantially as described. 75

In testimony whereof I hereunto affix my signature in the presence of two witnesses.

HARRY RANDOLPH VAN DEVENTER.
